UNITED STATES PATENT OFFICE.

CHARLES A. BRITTAINE, OF ST. LOUIS, MISSOURI.

RULED SHEET.

Application filed April 13, 1921. Serial No. 460,904.

To all whom it may concern:

Be it known that I, CHARLES A. BRITTAINE, a citizen of the United States, residing in the city of St. Louis, in the State of Missouri, have invented a new and useful Improvement in Ruled Sheets, of which the following is a full, clear, and exact specification, reference being had to the accompanying drawings, which form a part thereof.

10 My invention relates to ruled sheets and particularly to ruled sheets used in the preparation of statistical statements such as the results of audits, compilation of sales, stock records, daily production reports and many other tabulations.

15 Heretofore it has been impractical to use ruled sheets in a typewriter since the spacing of the rulings on the sheets did not conform to the spacings of the typewriter, and 20 there was necessarily a repeated rearrangement of the sheet to bring each separate ruling in register to receive the typewritten characters in the proper place.

25 The object of my invention is to provide a ruled sheet which will be adapted for use with a typewriter without repeated rearrangement of the sheet; to provide a ruled sheet in the use of which typewritten characters will register on any ruling without re- 30 arrangement of the sheet after the sheet is positioned so that typewritten characters will register on one ruling; to provide a sheet having rulings which will conform to the space units of a typewriter; and 35 to provide a sheet which will aid in the preparation of statistical statements and tabulations.

40 My invention is fully shown in the accompanying drawings where similar letters are used to designate similar parts. Fig. 1 is a plan view of my ruled sheet; Fig. 2 is a section of the sheet shown with columns of typewritten characters inserted in register with the rulings; Fig. 3 is a view of a section of a modified form of my ruled sheet 45 on which marginal caption spaces have been left.

50 Referring to the figures, A is a ruled sheet which forms the subject of my invention, having the binding marginal space B at the left hand side thereof and the top marginal space C. Within the marginal spaces are the marginal rulings D. The caption lines or spaces E are underneath and adjacent to 55 the top marginal space C. Within the mar-

ginal lines D are the horizontal rulings F and the vertical rulings G.

The horizontal and vertical rulings F and G are spaced apart to conform to the respective space units of a standard typewriter. The horizontal lines are preferably spaced so that the distance between adjacent lines is the same as the distance the sheet is made to travel in a typewriter by the turning of the typewriter platen through 60 a single line space. The vertical lines are preferably spaced apart a distance equal to three and one-half letter spaces in the horizontal movement of the typewriter carriage. There are seven figure spaces in two adjacent rectangles formed by the intersections of adjacent horizontal and vertical rulings F and G, allowing the insertion therein of 65 two units of three characters each with the width of one character as a spacing therebetween. 70

In Fig. 2 characters have been inserted to register with the horizontal rulings and to illustrate how three characters may be placed on the sheet between adjacent vertical 80 rulings. Any columnar arrangement, either horizontal or vertical may be obtained. 75

While in the drawings the horizontal rulings F are shown spaced apart a distance equal to a single space in the movement of a typewriter platen, and the vertical rulings G are shown spaced apart a distance equal to three and one-half letter spaces in the horizontal movement of a typewriter carriage, I do not propose to limit myself to 85 this spacing of the rulings. 90

Since the horizontal rulings F and the vertical rulings G are spaced apart to conform to the space units in the vertical movement of the typewriter platen and the horizontal movement of the typewriter carriage, respectively, if typewritten characters are made to register on or between any of the said rulings on the sheet A, other characters will register on or between any other rulings 95 without rearrangement of said sheet. The utility of this construction can be readily seen. In the preparation of statistical statements, such as those mentioned above, different columnar arrangements may be obtained 100 without rearrangement of the sheet A. A stenographer in preparing such statements registers one horizontal ruling F and one vertical ruling G on a sheet A, placed in a typewriter, with the point of contact of 105 110

the typewritten characters. When the position of the sheet in the typewriter is changed by the movement of the typewriter platen or the movement of the typewriter carriage, other typewritten characters may be made to register, without rearrangement of the sheet, with other horizontal and vertical rulings on any part of said sheet.

There are many uses to which the sheet 10 may be put, and there are many modified forms in which the sheet may be made. The marginal caption spaces shown in Fig. 3 may be placed at the right hand side of the sheet A instead of the left hand side thereof, 15 and the caption spaces E shown in Figs. 1 and 3 may be placed at the bottom of the sheet, or certain vertical or horizontal rulings F and G may be omitted to adapt the sheet to a particular use.

20 It is also obvious that the sheets may be adapted for use with any kind of typewriter or machine using type for writing on a sheet wherein the sheet and a part of the

machine have movements relative to each other in two directions.

25

What I claim as new and desire to secure by Letters Patent, is:

1. A sheet having thereon horizontal lines spaced to conform to the space units of the vertical movement of a typewriter platen 30 and having also vertical lines spaced to conform to the space units of the horizontal movement of a typewriter carriage and intersecting said horizontal lines.

2. A sheet having thereon intersecting 35 horizontal and vertical lines, said horizontal lines being spaced to conform to the space units in the vertical movement of a typewriter carriage and said vertical lines being spaced to conform to a space unit equal to three and one half letter spaces in the horizontal movement of a typewriter carriage.

In witness whereof I have signed my name to this specification.

CHARLES A. BRITTAINE.
